Primary Examiner — Cynthia Ramirez*Assistant Examiner* — Michael A Maharajh(74) *Attorney, Agent, or Firm* — Boudwin Intellectual Property; Daniel Boudwin(57) **CLAIM**

The ornamental design for a body building hammer, as shown and described.

DESCRIPTION

FIG. 1 shows a perspective view of a body building hammer. FIG. 2 shows a front view of the body building hammer.

FIG. 3 shows a rear view of the body building hammer.

FIG. 4 shows a right side view of the body building hammer.

FIG. 5 shows a left side view of the body building hammer.

FIG. 6 shows a top plan view of the body building hammer; and,

FIG. 7 shows a bottom plan view of the body building hammer.

The broken lines in the drawings are for the purpose of illustrating portions of a bodybuilding hammer which form no part of the claimed design.
